UNITED STATES PATENT OFFICE.

RALPH W. ENGSBERG, OF OAK PARK, ILLINOIS, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

Application filed September 29, 1923. Serial No. 665,530.

To all whom it may concern:

Be it known that I, RALPH W. ENGSBERG, a citizen of the United States of America, and a resident of Oak Park, Cook County, and State of Illinois, have invented certain new and useful Improvements in Automatic Telephone Systems, of which the following is a specification.

The present invention relates in general 10 to automatic telephone systems, but more especially to large automatic systems which employ both primary and secondary line switches for the purpose of connecting calling lines with idle first selector switches, 15 and may be considered as an improvement on Patent No. 1,275,186, issued to W. E. Lamb, August 6, 1918, and a pending application of T. G. Martin, Serial No. 452,468, filed March 15, 1921.

20 In systems of the above kind it is necessary to make all trunk lines incoming to a group of secondary line switches busy whenever all of the trunk lines outgoing from such secondary group are in use. It will be 25 appreciated that it is necessary to do this, since if calls were permitted to arrive at a group of secondary line switches when no trunks were available outgoing from such group, it would inevitably happen that such 30 calls would be lost, i. e., they could not be successfully completed. It is also necessary to provide means whereby the primary master switches are caused to pick up all the plungers of their respective idle switches 35 and bring them into locking engagement with their plunger shafts to prevent the possibility of such switches plunging in on busy trunks. This is accomplished by causing all the primary master switches to go thru a 40 complete cycle of operation each time all the trunk lines leading out of a secondary group become busy.

The arrangement shown in the above 45 patent for accomplishing this latter result has proven objectionable owing to the lapse of time between the operation of the first and last of the groups of primary master switches. It will be seen that during this interval a large number of plungers not yet 50 picked up could be plunged into bank contacts of trunks extending to the busy secondary group. A further objection is that since all groups of secondary switches have their pick up conductors permanently tied

to a common conductor, trouble on one of 55 these conductors is not readily located.

In the arrangement shown in the above referred to application the operating conductors of all primary master switches, and the pick up conductors of all secondary 60 groups are connected thru separate keys to a common conductor. A buzzer is associated with these keys in such a manner that should a permanent ground occur on either the operating or the pick up conductors, the 65 grounded conductor may be quickly found by operating the keys in succession, the buzzer not operating when the grounded conductor is disconnected.

The latter scheme has certain advantage 70 over that of the patent in that all primary master switches are operated simultaneously, and a convenient method of finding trouble is provided. It however has the great disadvantage of having all of the operating conductors of the primary switches 75 tied together and, therefore, if one of these conductors becomes grounded all primary master switches will operate regardless of whether a secondary trunk group is busy or 80 not. Another objection is the high manufacturing cost due to the large number of 85 keys and panel which are required.

The primary object of the invention therefore, is to provide simplified apparatus for 85 accomplishing the above desired results which may be manufactured more economically than any apparatus heretofore used.

Another object is to so design the apparatus that trouble on any particular primary group of master switches will not 90 affect the proper operation of any other primary group.

A still further object is to provide means for immediately locating a grounded conductor extending from a secondary group 95 by the operation of a single key, which at the same time, prevents the continued operation of all primary master switches.

The foregoing features will be described 100 hereinafter with reference to the accompanying figure of drawing, which shows sufficient of the apparatus in an automatic telephone system to enable the invention to be explained and understood.

105 Referring to the drawing more in detail, the reference character A indicates an automatic telephone substation of the

ordinary type having the usual talking instrumentalities and a calling device S for controlling the automatic switches at the exchange. The line conductors 11 and 12 5 terminate at the exchange in the individual line switch C, which is a line switch of the well known Keith or plunger type, and hence will not need to be described in detail. Briefly stated the function of the 10 line switch C is to extend the associated line when calling to an idle trunk line. In accordance with the usual practice, the lines entering the exchange are divided into groups, and all of the line switches associated with the lines in each group may be 15 controlled in their trunk selecting operations by a common master switch. The master switch which is associated with the group which includes the line switch C is 20 shown in the lower left hand corner of the sheet and is indicated by the reference character E. This master switch is of the well known solenoid type such as is in common use in the automatic telephone exchanges 25 throughout the country.

Secondary line switches are employed in the present system and accordingly the trunk lines from the primary line switchboards will extend to secondary line switches 30 rather than to first selector switches. The arrangement of the trunking between the primary and secondary line switchboards is well understood. There may be a plurality of groups of secondary line 35 switches and each group of primary line switches will have outgoing trunks extending to secondary line switches in each secondary group, so that any calling subscriber will be given access to the trunk lines outgoing from all of the secondary groups. In this manner a large number of first selectors, say one hundred or more, may be combined in one large group thus securing an increased trunking efficiency. The advantages gained by the use of secondary line 40 switches, however, are well known and need not be discussed in detail.

One of the trunk lines outgoing from the primary group which includes the line 45 switch C is shown in the drawing, and extends to the secondary line switch D. The line switch D is of the well known rotary type, having wipers which normally stand on the trunk line last used, and which move in a forward direction only. There are a 55 number of relays and lamps in the lower right hand portion of the drawing which have certain functions to perform when all of the trunk lines outgoing from the secondary line switch group which includes the line switch D become busy, and at other times. It will be convenient, however, to go into this later on during the explanation 60 of the operation of the system.

Having described the apparatus involved

briefly, its operation will now be described more in detail with a view to pointing out the particular features of novelty disclosed herein. For this purpose it will be assumed that the subscriber at substation A desires to call 70 some other subscriber in the system, and the operation of the primary and secondary line switches C and D in connecting the line of substation A to a trunk line extending to a first selector switch will be described. When 75 the receiver is removed at substation A a circuit is completed over the line conductors 11 and 12 for the line relay 16 of the line switch C. Upon energizing, the line relay 16 closes a circuit for the pull in winding 80 18 of the line switch at armature 25. Upon energizing, the pull in winding operates both the cut-off armature 24 and the plunger arm 23, the former being effective to disconnect the line conductors 11 and 12 from the winding of the line relay and from the grounded common conductor 46, respectively; while the latter forces the bank springs 30, 31, 32, and 33 into engagement with contacts 34, 85 35, 36, and 37, respectively. By the engagement of bank springs 30 and 33 with contacts 34 and 37, the line conductors 11 and 12 are extended into connection with the trunk line conductors 40 and 42, and a circuit is accordingly completed for the line 90 relay 50 of the secondary line switch D. The line relay 50 is accordingly energized and at its armature 53 closes a holding circuit for the line switch C, which may be traced from ground by way of the working contact of armature 53 and the said armature, normally closed contact springs controlled by armature 58, release trunk conductor 41, contact 35, bank spring 31, and the holding winding 17 of the line switch C 95 to battery. This holding circuit is established before the slow acting line relay 16 of the line switch C has time to deenergize and is effective to retain the plunger arm 23 and the cut-off armature 24 in operated 100 position. A ground potential is also placed on the private normal conductor 15 which extends to multiple test contacts in the banks of the connectors which have access to the line of substation A, whereby the line is 105 guarded against intrusion in the customary manner. Another circuit closed by the operation of the line switch C is completed by the engagement of bank spring 32 with contact 36. This places a ground on conductor 110 43 and a circuit is thus completed by way of the master switch test wiper 108 and the left-hand winding of the starting relay 100 to battery. Relay 100 is accordingly energized and at its left-hand armature completes a circuit for the locking relay, or magnet 101. As is well understood, when the locking relay is energized it releases the master switch shaft (controlling all the idle line switch plungers) and the shaft instantly 115 120 125 130

turns in a counter clock-wise direction under control of a governor, the operating force being supplied by a heavy spring under tension. The test wipers 108 and 107 are attached to this shaft, from which it will appear that these test wipers will immediately be moved off from their associated tenth test contacts and into engagement with the associated ninth test contacts. Assuming that the ninth trunk line is idle, there will be no ground potential on the ninth test contacts, the starting relay 100 will deenergize to open the circuit of the locking relay 101, and the latter relay will deenergize to again lock the master switch shaft. It may be pointed out in this connection that when the locking relay 101 is energized it closes a circuit for the "open main" relay 103 which disconnects the common conductor 44 from the nongrounded pole of the battery. This is to prevent the operation of any other line switches while the master switch shaft is being moved from one trunk to another by the master switch.

Continuing now with the operation of the secondary line switch D, when the line relay 50 is energized as explained hereinbefore, it closes a circuit at its armature 54 which includes the winding of the switching relay 51 and the winding of the stepping magnet 52 in series, while at the same time by means of armature 55 the test wiper 66 is connected to this circuit at a point midway between the said relay and the said magnet. The operation now depends upon whether the trunk line with which the line switch wipers are associated is busy or idle. If this trunk line is busy there will be a ground potential on the test contact engaged by test wiper 66, such as test contact 69 for example, the switching relay 51 will be short circuited, and the stepping magnet 52 being supplied with direct ground via the test wiper will operate in the manner of a buzzer to advance the switch wipers step by step in search of an idle trunk line. This movement will continue as long as the test wiper 66 continues to engage grounded test contacts. When the wipers arrive at an idle trunk line, which we may assume is the trunk line comprising conductors 77, 78, and 79, the test wiper 66 will find no ground potential on the test contact 72, the rotation of the switch will cease and the switching relay 51 being no longer short circuited will energize in series with the stepping magnet 52, the latter remaining inoperative on account of the high resistance of the switching relay. Upon energizing, relay 51 connects the incoming release trunk conductor 41 to the test wiper 66 by means of armature 58, and at armature 57 connects its own lower terminal to the now continuous conductor extending from the test wiper 66 back over conductor 41 to the line switch C. The line relay 50 be-

ing still energized, the test wiper 66 is connected to ground by these operations in order to render the selected trunk line busy. In addition to the foregoing, at armatures 56 and 59 relay 51 disconnects the incoming trunk conductors 40 and 42 from the windings of the relay 50 and from ground, respectively, and extends them by way of wipers 65 and 67, bank contacts 71 and 73 and conductors 77 and 79 to the line relay 75 of the first selector switch in which the selected trunk line terminates. Although this switch is not shown, its operation is well understood and it will be sufficient to state that the line relay of the selector is energized over the circuit of the calling line and closes a circuit for the associated slow acting release relay. The latter relay, upon energizing, places a ground potential upon the release trunk conductor 78, thereby establishing a holding circuit for the switching relay 51 of the secondary line switch D, and for the holding winding 17 of the primary line switch C. This holding circuit, it will be understood, is established before the slow acting line relay 50 has had time to deenergize.

The remainder of the operations in which the calling subscriber controls the first selector taken for use, and a plurality of other automatic switches through the medium of his calling device S, to complete the connection to the desired called line, are well understood and as they have nothing special to do with the present invention, these operations will not be further considered, except to say that when the calling subscriber has finished talking, the restoration of his receiver to the switch-hook causes the automatic switches to restore to normal with the result that ground is disconnected from the release trunk conductor 78. This operation breaks the holding circuit for the primary and secondary line switches C and D and the said switches are restored to normal position, it being understood that the restoring operation of the secondary line switch D consists merely in the deenergization of the switching relay 51.

As previously pointed out, it is necessary to make all trunk lines incoming to a group of secondary line switches busy whenever all of the trunk lines outgoing from such secondary group become busy. The arrangement for accomplishing this in the present case is the same as the method used in the pending application previously referred to, and consists of a series of chain relays 80, 81, etc., and control relays 83, 84 and 85. There is one chain relay for each trunk outgoing from a secondary group. These chain relays are connected, one to each of the release trunk conductors and as fast as the trunk lines become busy will energize, and when all of the trunk

- lines are busy all of the chain relays will be energized, with the result that ground is placed on the conductor 82, thus closing an energizing circuit for the relay 83. 5 Upon energizing, relay 83 closes at armature 89 a circuit for relay 85, which upon attracting its armatures connects ground to the conductor 93. The release trunk conductor 41 of the trunk line which terminates 10 in the secondary line switch D is normally connected to the conductor 93, and if the trunk line is not otherwise engaged it is made busy anyway. Relay 85 may be a large multiple contact, or gang relay, or a 15 number of relays connected in series or parallel may be used; at any rate, at the same time that conductor 93 is grounded similar conductors extending to all of the remaining secondary line switches in the 20 same group are grounded also, thus making all of the trunk lines incoming to the group in question busy.
- As a further result of the energization 25 of relay 83, upon all of the trunk lines becoming busy, the conductor 92 is grounded for the purpose of bringing about the operation of the master switches in all of the primary groups from which trunk lines lead to the particular secondary group in 30 question. The slow acting relay 84 is normally energized, but when relay 83 attracts its armature the circuit of relay 84 is broken. Relay 84, however, does not retract its armature immediately and in the meantime 35 relay 83 places ground on conductor 92 by means of its armature 88. The grounding of conductor 92 is only momentary as ground is taken off at armature 86 as soon as relay 84 falls back. When conductor 92 40 is grounded in this manner a circuit is completed for relay 111. This circuit extends from the grounded conductor 92, lamp L', conductor 200 and the winding of relay 111 to battery. The resistance of relay 111 is 45 such that lamp L' does not glow over this circuit. Relay 111, however, operates and, at its armature 112 applies ground to the operating conductor 94 of each of the primary master switches, thereby completing 50 a circuit for relay 102 in each such switch. Upon energizing, relay 102 establishes a locking circuit for itself at its armature 120 and at its armature 121 closes the circuit of the locking relay 101. Upon energizing, relay 101 closes a circuit for the 55 "open main" relay 103 and at the same time unlocks the master switch shaft mechanically so that it is free to move to the left, or in a counter clock-wise direction, 60 under control of the main spring and governor, as previously explained. Since relay 102 has been locked in energized position, this movement will continue until the wipers 107 and 108 arrive at the first 65 test contacts in their respective banks at

which time the line switch plungers will be opposite the first trunk. The arm 122 now closes contact springs 124 and 125, thus completing a circuit for relay 104. When relay 104 attracts its armature, the armature is locked in operated position behind the tooth on spring 126 so that the relay remains in operated position after its energizing circuit is broken. The energization 70 of relay 104 breaks the locking circuit of relay 102, permitting this relay to fall back, and also closes a new circuit for the locking relay 101, in order that this latter relay may be held up after the relay 102 has de-energized. In addition, relay 104 closes a 75 circuit for the solenoid 106. Upon the energization of the solenoid, the master switch shaft is rotated by a continuous movement in a clock-wise direction until all of the plungers are lined up opposite the tenth 80 trunk, wipers 107 and 108 being restored to the position shown in the drawing. The arm 123 now disengages spring 126 from the armature of relay 104 and this armature is released to break the circuit of the solenoid 106 and the circuit of relay 101. Relay 101 now deenergizes and locks the 85 shaft in position opposite the tenth trunk. Obviously when the primary master switches are operated, any line switch plungers which happen to be disengaged from the shaft are "picked up" and are again brought under the control of the master switch so that there will be no danger of any of them being plunged in on busy trunk lines. 90

The features of the invention lie in the provision and arrangement of multi-contact relay 111, key K, and lamps L', L², etc., the purposes of which will now be fully explained. Assuming there are five groups of secondary line switches, and twenty-five or more groups of primary line switches, it will be clear that there will be five branches corresponding to conductors 92, and twenty-five or more branches corresponding to conductor 94. It will be evident that since the conductors 94 are connected together momentarily, only when all of the primary switches are to be operated, that should a conductor 94 become locally grounded only 100 the one primary master switch will be operated and consequently only the subscribers associated with that particular group will be unable to complete connections. Since only one primary master switch will be continuously operating when the usual alarm signal notifies the attendant of trouble the master switch in trouble may be readily located. 105

The conductors 92 it will be noted are each connected thru an individual lamp such as L' to common conductor 200. In case a conductor 92 becomes permanently grounded it will cause the continuous operation of relay 111 and the resultant continued op- 110

eration of all primary master switches. The operator upon receiving the appropriate alarm simply operates key K to the left thereby opening the circuit for relay 111 causing the master switches of all primary groups to stop as soon as they have completed a cycle of operation. The key also at the same time closes a circuit for any lamp L¹, L², etc., associated with a grounded conductor, thereby informing the attendant where the trouble lies.

The key K, in addition to being used for locating grounded conductors 92, may also be operated to the right, in which case it functions as an emergency "pick up" key, and is useful to the attendant for trying the operation of the primary master switches, and may also be used in case the regular circuits for automatically operating these master switches should get out of order. The exchange is always equipped with various supervisory signals and alarms which indicate the blowing of fuses or the busy condition of trunks groups, etc. The attendant is thus, at all times, aware of the condition of the equipment and in case some of the automatic devices fail to perform their functions he may accomplish the desired results by means of key K.

In case all of the trunks outgoing from the primary line switch group are busy all of the test contacts in the bank associated with test wiper 107 will be grounded, and the starting relay 100 will remain energized as long as this condition exists. When relay 100 is energized it closes a circuit for the locking relay 101 in order to initiate the operation of the master switch as previously explained.

Having described the invention, what is considered to be new and is desired to have protected by Letters Patent will be pointed out in the appended claims.

What is claimed is:

1. In combination, a relay, a plurality of branch operating circuits for said relay, lamps included in series with said circuits, means for momentarily applying a potential to any one of said branches to cause the operation of said relay, and means for simultaneously removing all of said branches from connection with said relay should said potential remain on any branch, said last means also effective to close a circuit for the particular lamp associated with the branch having a potential thereon.

2. In combination, a relay, a plurality of branch operating conductors permanently tied together thru lamps connected in series with said relay, means for momentarily applying a ground potential to any of said branches to operate said relay, and means for causing any of said lamps which are connected to a branch having a ground po-

tential thereon to glow, said last means also being effective to open the circuit of said relay.

3. In combination, a relay, a plurality of branch operating circuits provided with a like plurality of lamps, each branch having one end connected to a terminal of its respective lamp, a common conductor extending from said relay to the other terminal of each of said lamps, means for applying a potential to any branch for operating said relay, and means for removing the relay from said circuit and substituting a potential for causing any lamp to glow which is associated with a branch conductor having a potential thereon.

4. In a telephone system, primary line switches divided into groups, a master switch for controlling each group of line switches, secondary line switches divided into groups, trunk lines leading from said primary to said secondary line switches, secondary trunk lines leading out of said groups of secondary line switches, a relay for completing operating circuits for each of said master switches, and means operable when all the secondary trunk lines leading from any group are in use for causing a momentary operation of said relay.

5. In a telephone system, primary line switches divided into groups, a master switch for controlling each group of line switches, secondary line switches divided into groups, trunk lines leading from said primary to said secondary line switches, secondary trunk lines leading out of said groups of secondary line switches, a circuit for causing each of said master switches to sweep over all of the trunk lines of its respective group of primary switches while some of said last trunks are idle, a relay for causing said circuit to be completed, and means operable when all of the secondary trunk lines outgoing from any group are in use for causing the operation of said relay.

6. In a telephone system, primary line switches divided into groups, a master switch for controlling each group of line switches, each such master switch having an operating conductor, a multi-contact relay for simultaneously tying together and grounding all of said conductors to cause said switches to operate, secondary line switches divided into groups, trunk lines leading from said primary to said secondary line switches, secondary trunk lines leading out of said groups of secondary line switches, and means for causing the operation of said relay when all the secondary trunk lines of a group are in use.

In witness whereof, I hereunto subscribe my name this 26th day of September, A. D. 1923.

RALPH W. ENGSBERG.
